UNITED STATES PATENT OFFICE.

GEORGE G. BAILEY, JR., AND JAMES GILBERT, OF BOSTON, MASS.

DESIGN FOR A FONT OF PRINTING-TYPES.

Specification forming part of Design No. 11,470, dated October 21, 1879; application filed September 11, 1879.
[Term of patent 7 years.]

To all whom it may concern:

Be it known that we, GEORGE GARDNER BAILEY, Jr., and JAMES GILBERT, of Boston, Suffolk county, State of Massachusetts, have invented a Design for a Font of Printing-Types, (which we call "Moravian" type,) of which the following is a full, clear, and exact description, reference being had to the accompanying illustration, making part of this specification.

The following is a description of our new font of types: The letters are all capitals, or "upper-case." They have each a dot on top and bottom, connected by curved lines with the body, except the letters C, G, Q, T, Z, and character &. The broad line of each letter runs below the horizontal base line, with a spur and a dot attached, except in the letters A, C, J, M, N, O, Q, S, U, V, W, X, and Z, which, with the exception of Q, have each a hair-line running below the base. The right-hand broad line of the letter H projects above the top horizontal line, and has a dot attached. The cross-lines of the letters A, E, F, and H project through the letter to the left, with a pin-head-like ornament at the end. The single body-lines and the left-hand body-lines of the respective letters, where the lines are double, are not filled in or rounded at the inner corners at their junction with the horizontal baseline. The letters K, N, U, V, W, X, and Y have at their tops a spur proceeding diagonally upward at the right-hand side.

What we claim as our invention is—

The design for a font of printing-types, substantially as described.
